UNITED STATES PATENT OFFICE.

JOHN O. HUNT, OF BROOKLYN, NEW YORK, ASSIGNOR TO INDEPENDENT PAPER MILLS INC., OF BROOKLYN, NEW YORK, A CORPORATION OF NEW YORK.

DISPENSER FOR PAPER NAPKINS, TOWELS, AND THE LIKE.

Application filed October 10, 1924. Serial No. 742,737.

To all whom it may concern:

Be it known that I, JOHN O. HUNT, a citizen of the United States, residing in the borough of Brooklyn, county of Kings, city 5 and State of New York, have invented an Improvement in Dispensers for Paper Napkins, Towels, and the like, of which the following is a specification.

My present invention relates to a dispenser for paper napkins, towels and like articles, and particularly to a type of dispenser especially adapted for commercial use in which the articles whether they be towels, napkins or similar devices are available to be withdrawn from the top or upper end of the dispenser one at a time. The invention furthermore relates to that type of dispensers for napkins, towels and like articles in which the articles in a superimposed pile are placed on a movable platform which is automatically raised as the articles are withdrawn from the dispenser in order to maintain the uppermost article in a substantially uniform position in which it may 25 be readily withdrawn by the person desiring to use the same.

In carrying out my present invention I employ a motor device, together with means for connecting the same to the platform for automatically raising the platform the construction being such that when the platform is lowered the motor is wound. The invention furthermore relates to devices against which the napkins or towels or similar articles at the upper end of the superimposed pile are brought to bear and which devices are actuated by the pressure exerted through the pile of articles by the platform in order to control the operation of the motor, the 40 motor being released to raise the platform and lift the superimposed pile of articles thereon when the uppermost article is at a predetermined level and causing the motor to stop when the platform has been raised sufficiently far to bring the uppermost article in the predetermined pile thereof on the platform to a predetermined height, as will be hereinafter more particularly described.

50 In the drawing:

Fig. 1 is a sectional plan taken approximately on the line 1—1, Fig. 2 and illustrating an apparatus made in accordance with my present invention.

Fig. 2 is a sectional elevation taken approximately on the line 2—2, Fig. 1. 55

Fig. 3 is also a sectional elevation taken on the line 3—3, Fig. 2.

Fig. 4 is a sectional plan taken on the line 4—4, Fig. 2. 60

Fig. 5 is a sectional elevation on the line 5—5, Fig. 4.

Fig. 6 is a sectional elevation on the line 6—6, Fig. 4.

Fig. 7 is a sectional elevation on the line 7—7, Fig. 1, showing the parts, however, on a somewhat larger scale, and 65

Fig. 8 is a view similar to Fig. 7 showing the parts as illustrated therein in a different position. 70

Referring to the drawing, it will be seen that in carrying out this invention the dispenser made in accordance therewith is housed within a suitable casing which may be constructed to include a base 10 mounted on feet or supports 11 and having side walls 12 and a top member 13. The top member is preferably apertured and provided with a transverse bar 14 dividing the apertured top into the openings 15 and 16 through which the napkins, towels or other articles to be dispensed are withdrawn. As illustrated the dispenser includes two separate and distinct mechanisms. This is for the purpose of utilizing two superimposed piles 80 of napkins, towels or like articles in one and the same apparatus and making it possible to dispense the articles from either pile independently of the other. It will be understood, however, that the apparatus may be 85 so constructed as to include one, two or more piles of superimposed articles without departing from the nature of the invention. 90

Within the casing there is a skeleton framework comprising a bottom plate, a top plate and a plurality of uprights or posts connecting the same. The bottom plate is indicated at 17. The top plate preferably comprises oppositely disposed longitudinal rails 18 and 19 and transverse rails 20 and 21, together with an intermediate transverse rail 22. The posts connecting the bottom and top plates are arranged in sets. The posts in one set thereof are designated by the reference numerals 23, 24, 25, 26, 27, and 28. The posts included in the other set thereof are designated by the reference numerals 27, 28, 29, 30, 31 and 32, it being noted that the cen- 100 105

trally disposed posts 27 and 28 are utilized in both sets of posts. These posts, as hereinbefore stated, extend between the bottom plate 17 and the top plate and are secured thereto in any suitable manner. These posts also act as guide members for the platform, as will be hereinafter more particularly described. Extending upwardly from the base or bottom plate 17 I also prefer to employ suitably spaced posts 33 and 34 and 35 and 36 which function as stop posts to limit and determine the lowermost positions of the platforms, as will also be hereinafter more particularly described. As shown in Fig. 1 of the drawing this skeleton framework is secured in position in the casing by lugs 37 and 39 extending laterally from the longitudinal rails 18 and 19 and connected respectively to the walls of the casing by screws 38 and 40 or otherwise.

I also employ suitable platforms upon which the napkins, towels or other articles are placed and are supported and automatically raised to position to be taken from the dispenser for use. In the apparatus as herein shown and described, there are two such platforms and they are similarly constructed. One platform, for example, comprises an upper and a lower plate 41 and 42 respectively which are connected in a spaced relationship by spacer bolts 43 or otherwise. The other platform consists of an upper plate 44 and a lower plate 45 connected in a spaced relationship by the spacer bolts 46 or otherwise. In suitable positions the edges of these platform plates are semi-circularly notched to receive portions of the uprights or guide posts therein. For example, one edge of the plates 41 and 42 is notched to receive the guide posts 24 and 25, the end edges of the plates 41 and 42 are notched to receive portions of the guide posts 23 and 26, while the opposite edges of the plates 41 and 42 are notched to receive portions of the guide posts 27 and 28. The edges of the plates 44 and 45 of the other platform are similarly notched to engage portions of the guide posts 27, 28, 29, 30, 31 and 32. These platforms, as hereinbefore stated, are adapted to receive and support piles of superimposed napkins, towels or other articles of like nature which are designated at 47 and 48.

Each dispenser apparatus is provided with a motor which is preferably a spring motor of the clock mechanism type. These motors are identical in structure and therefore but one of them will be described in detail. Each of these motors as illustrated comprises a set of base plates 49, 50 suitably secured to the bottom plate 17 and provided with uprights 51 and 52 connected together and spaced by spacer bars 53 or otherwise. This motor frame is preferably completed by a top member 53'. Suitably journaled in the uprights 51 and 52 there is a shaft 54 fitted

with a sleeve 55. The motor also includes sets of springs 56, 57. At one end each of these springs is connected to the shaft 54 by a pin 58 or otherwise, while the opposite end of each of these springs is suitably connected to a post 59 secured in and extending from one of the uprights. Also mounted on the shaft 54 there is a ratchet 60. This ratchet is provided with a pawl 61, the end of which is normally maintained in contact with the teeth of the ratchet by a spring 62 or otherwise. The motor mechanism also includes drums 63 and 64 mounted on the shaft 54 exteriorly of the springs. Also mounted on the shaft 54 is a gear wheel 65. This gear wheel 65 drives a train of gears and pinions, the arbors of which are mounted in the uprights of the motor and which terminate in a brake wheel 66 mounted on an arbor 67 which is also journaled in the said uprights. Associated with the brake wheel 66 there is a spring brake band 68 forming a continuation of a plate 69 preferably secured to the top member 53' and provided with a depending extension 70 to be engaged, as hereinafter described, in such a manner as to apply the brake band to the brake wheel to stop and also to release the motor.

Each motor is suitably connected to the platform associated therewith so as to automatically raise the same when the motor is released and permitted to operate. The motor devices and their platforms are connected by suitable chains, cords or other flexible devices. As illustrated one end of a cord or chain is attached to and wound upon the drum 64. This cord or chain 71 passes under a pulley 72 mounted in a bracket 73 and also passes over a pulley 74 which is mounted in a bracket 75 secured to the transverse rail 20 and the opposite end of this cord or chain 71 is suitably connected to the upper plate 41 of the left hand platform as shown in Fig. 3 of the drawing. In a similar manner one end of a cord or chain 76 is connected to and wound upon the drum 63. This cord or chain 76 passes over a pulley 77 which is mounted in a bracket 78 depending from the transverse rail 22, and the opposite end of the cord or chain 76 is connected to the upper plate 41 of this platform as indicated at 79 in Fig. 3 of the drawing. The other platform is similarly connected to the other motor device. A cord or chain 80 has one end thereof secured to and passed around a drum 81. This cord or chain 80 also passes under a pulley 82 mounted in a bracket 83 and over a pulley 84 mounted in a bracket 85 depending from the transverse rail 21 and this end of the cord or chain 80 is suitably connected to the upper plate 44 of the right hand platform as shown in Fig. 1 of the drawing. Also a cord or chain 86 at one end thereof is secured to and passed around a drum 87,

while at its other end this cord or chain is passed over a pulley 88 mounted in a bracket 89 depending from the central transverse rail 22 and at its extremity is suitably connected to the upper plate 44 of this platform.

The dispenser made in accordance with my present invention is particularly adapted for use with napkins or towels folded in a special manner in which each napkin or towel as folded preferably includes a plurality of sections of equal extent and an outer section which is not coextensive with the other sections and which outer section is also provided with a fold whereby two oppositely disposed edges are provided, either one or both of which may be grasped by the user in taking and withdrawing a napkin or other article from the dispenser. The napkins are preferably folded so as to assume a rectangular configuration and the outermost non-coextensive section is folded to extend longitudinally of the napkin. The napkins when placed in the dispenser in a superimposed pile assume positions in which the centrally disposed non-coextensive section of the uppermost napkin or other article is readily available for use. Also in carrying out the invention I employ rocker bars placed in the apparatus so as to be normally engaged by the oppositely disposed longitudinal edge portions of the uppermost napkin in the superimposed pile and to be actuated by the pressure exerted by the pile of napkins through the movement of the platform to control the operation of the motor in such a manner that when the outermost napkin reaches a predetermined position the rocker bars are moved to actuate the said devices in such a manner as to stop the motor thereby also stopping the movement of the platform and when sufficient napkins or other articles have been withdrawn to cause the outermost napkin to then assume another position, the rocker bars being relieved of the pressure exerted against them by the napkins permit the actuation of the said devices to release the motor by causing the same to again move the platform and advance the napkins to such a position that the rocker bars again actuate the said devices to stop the motor.

The rocker bars are designated at 90, 91, 92 and 93. The rocker bars 90 and 91 are part of one of the independent dispensing devices of the apparatus and the rocker bars 92 and 93 of the other. The rocker bar 90 is pivotally mounted at its ends as indicated in the drawing, being provided with similarly placed pins 94 and 95 journaled in the longitudinal rails 18 and 19 for this purpose. At the ends thereof the rocker bar 90 is also provided with guide pins 96 and 97 operating respectively in slots 98 and 99 provided for this purpose in the longitudinal rails 18 and 19. The rocker bar 91 is similarly

mounted, being provided with pins 100 and 101 journaled in the longitudinal rails 18 and 19 and also being provided with guide pins 102 and 103 moving in slots 104, 105 provided for this purpose in the longitudinal rails 18 and 19. The rocker bar 92 at the ends thereof is provided with pins 106 and 107 by which this rocker bar is pivotally mounted in the longitudinal rails 18 and 19. Also at the end of this rocker bar there are 70 guide pins 108 and 109 moving in slots 110 and 111 provided for this purpose in the longitudinal rails 18 and 19. Likewise at the ends thereof the rocker bar 93 is provided with pins 112 and 113 journaled in the 75 longitudinal rails 18 and 19 and also with guide pins 114 and 115 moving in slots 116 and 117 provided for this purpose in the longitudinal rails 18 and 19. As clearly appears in Fig. 1 of the drawing each set 80 of these rocker bars is adapted along the inner or adjacent edges thereof to bear against the outer longitudinal portion of the outer napkin or other article to be taken from the dispenser and furthermore that 85 the position of the sets of rocker bars is dependent upon the position of the uppermost or outermost napkin or other article which in turn depends upon the position of the platform.

The rocker bars or one of the rocker bars of each set is employed to actuate devices for controlling the motor. As illustrated, the rocker bar 93 is provided with a finger or projection 118 extending from the outer edge thereof in a slightly offset position. This finger 118 is adapted to engage the upper end 119 of a lever 120. The lever 120 is pivotally mounted in any suitable manner in the transverse rail 21. As illustrated the 100 transverse rail in a substantially central position in the lower end thereof has an inset piece 121 secured therein. The lever 120 is pivotally mounted as indicated at 122 between this inset piece and the adjacent portion of the transverse rail 21, the rail being recessed as indicated at 123 and the inset piece being recessed as indicated at 124 to permit the lever 120 to swing on its pivotal point. We also employ a rocker bar 125. 105 This rocker bar is suitably mounted at its upper and lower ends preferably in the bottom plate 17 at its lower end and in the transverse rail 21 at its upper end. The inner or lower end of the lever 120 is connected to the rocker bar 125 by a link 126 or otherwise. At the lower portion of the rocker bar 125 the same is fitted with an arm 127 so placed and of an extent sufficient 110 to bear against the projection 79 of the brake band 68 for controlling the operation of the motor B which moves the platform in the right side of the machine as viewed in Fig. 1. A similar construction is employed 120 in the other dispensing apparatus, that is 125 130

to say the one in the left side of the machine as viewed in Fig. 1. In this side of the machine the finger extending from the rocker lever 90 is designated at 128. This contacts 6 with the upper end of a lever 129 pivotally mounted in the transverse rail 20 and this lever 129 is connected by a link 130 with a rocker bar 131 mounted at its lower end in the bottom plate 17 and at its upper end in 10 the transverse rail 20. The rocker bar 131 is provided with an arm 132 which is so placed and of such an extent as to contact with the projection or extension 70 of the resilient 15 brake band 68 of the motor A which operates the platform of the left hand dispensing device as viewed in Fig. 1.

Now, as will be apparent, when the platform, for example, in the right hand dispensing device as viewed in Fig. 1 has been 20 raised sufficiently far to cause the napkins to assume the position shown in Fig. 7, the rocker bar 93 will be swung upwardly or outwardly to the position illustrated in this figure. In so doing, the lever 120 will be 25 swung in a clockwise direction and through the link 126 will cause the rocker bar 125 to turn a partial revolution in the same direction. This will impart a like movement to the arm 127 thereby causing the same to 30 bear against the extension of the brake band of the motor B to cause the brake band to bear against the brake wheel 66 with sufficient friction to stop the motor thereby also stopping the movement of the platform. 35 Obviously also when the napkins or other articles have been withdrawn from the dispenser to a sufficient extent to permit the rocker lever to move in the opposite direction the finger or projection 118 will move out of 40 contact with the lever 120 and through the resilient action of the extension of the brake band the parts will move in the directions opposite to that hereinbefore described, releasing the motor and permitting the same 45 to operate to advance the platform until the napkins or other articles are again brought into contact with the rocker bars with sufficient pressure to operate the parts as hereinbefore described and again stop the 50 motor.

In order to prevent the rocker bars 90 to 55 93 inclusive from moving downwardly or inwardly so far when the superimposed napkins or other articles are placed in the dispenser as to make it necessary to replace or reset these rocker bars, I prefer to employ means, and preferably resilient means, for limiting the inward or downward movement 60 of the said rocker bars. As illustrated in the drawing, these means may constitute sets of springs. For example, as illustrated, springs 133 and 134 are secured respectively to the inner or under surfaces of the longitudinal rails 18 and 19 and the guide pins 96 65 and 97 of the rocker bar 90 may bear against

and press upon these springs when the rocker bar is depressed in placing the napkins or similar articles in the dispenser. The springs 133 and 134 may be secured to the longitudinal rails 18 and 19 by screws as indicated, or otherwise. Similarly springs 135 and 136 are provided for the lever bar 91, the guide pins 102 and 103 of which may be brought to bear against these springs. The set of springs for the lever bar 92 are indicated at 137 and 138 and in like manner the guide pins 108 and 109 of this rocker bar may bear against these springs. The other set of springs or that for the rocker bar 93 are designated at 139 and 140 and in a similar manner the guide pins 114 and 115 of this rocker bar may bear against this set of springs.

The invention as illustrated embodies a dispenser in which, as hereinbefore stated, 85 there are two independent dispensing devices. Nevertheless, it will be understood that one or any number of similarly constructed dispensing devices may be employed. Also, as herein shown and described, the dispensing apparatus is so arranged and constructed that the napkins, towels or similar articles are placed in superimposed piles and when the motors are released and permitted to operate the platforms are raised to lift the napkins or other articles, but the apparatus may be otherwise constructed to place the platforms, for example, in a vertical position and to move them horizontally forcing the napkins or other articles to an opening in the side of the apparatus rather than in the top thereof. Obviously also, other details of construction may be employed without departing from the nature and spirit of the invention.

I claim as my invention:

1. In a dispenser for paper napkins, towels and like articles, a platform, a motor for moving the platform for advancing a pile of napkins, towels and the like placed on the platform, and devices actuated by the advance of the pile of napkins, towels and the like, and extending between the outermost article and the motor for controlling the operation of the motor, causing the motor to be operative to move the platform

when the outermost article thereon is in one position, and causing the motor to be inoperative when the outermost article has been advanced by the motor to another position.

2. In a dispenser for paper napkins, towels and like articles, a platform adapted to advance a pile of napkins, towels and the like placed thereon, a motor, means for connecting the motor to the platform whereby the motor moves the platform and advances the pile of napkins, towels and the like, and devices actuated by the advance of the pile of napkins, towels and the like, and extending between the outermost article and the

motor for causing the motor to be operative to move the platform when the outermost article is in one position, and causing the motor to be inoperative when the outermost article has been advanced by the motor to another position.

3. In a dispenser for paper napkins, towels and like articles, a vertically movable platform adapted to support a pile of napkins, towels and the like placed thereon, a motor for raising the platform, and moving the pile of napkins, towels and the like, and devices actuated by the lifting of the napkins, towels and the like, and extending between the outermost article and the motor for controlling the operation of the motor, causing the motor to be operative to move the platform upwardly when the uppermost article is in a predetermined position, and causing the motor to be inoperative when the uppermost article has been lifted by the motor to another position.

4. In a dispenser for paper napkins, towels and like articles, a platform adapted to support a pile of napkins, towels and the like placed thereon, a motor, means for connecting the platform to the motor whereby the motor moves the platform to raise the pile of napkins, towels and the like thereon, and devices actuated by raising the pile of napkins, towels and the like, and extending between the outermost article and the motor, causing the motor to be operative to move the platform when the outermost article is in one position, and causing the motor to be inoperative when the outermost article has been raised by the motor to another position.

5. In a dispenser for paper napkins, towels and like articles, a platform, a motor for moving the platform to advance a pile of napkins, towels and the like, rocker bars adapted to bear along corresponding edges thereof against the oppositely disposed side portions of the outermost article in the pile thereof, and devices operated by the said rocker bars for controlling the operation of the motor permitting the motor to be operative to move the platform and advance the pile of articles when the outermost articles are in a predetermined position and to cause the motor to be inoperative when the said outermost article is in another predetermined position.

6. In a dispenser for paper napkins, towels and like articles, a vertically movable platform, a motor, means for connecting the platform to the motor in such a manner that when operative the motor raises the platform to lift a pile of superimposed napkins, towels and the like placed thereon, rocker levers pivotally mounted and adapted at corresponding edges to bear against the opposite edge portions of the uppermost article in the said superimposed pile thereof, and devices operated by the said rocker levers

for controlling the said motor permitting the motor to operate to raise the said platform and lift the articles placed thereon when the uppermost article is in a predetermined position and causing the motor to be inoperative when the platform has been raised sufficiently far to bring the uppermost article into another predetermined position.

7. In a dispenser for paper napkins, towels and like articles, a vertically movable platform, a motor, means for connecting the platform to the motor whereby when operative the motor raises the platform to lift a pile of superimposed paper napkins, towels and like articles placed thereon, a pair of oppositely disposed pivotally mounted rocker levers each adapted at one edge to bear against opposite edge portions of the uppermost article in the superimposed pile thereof, and devices operated by one of the said rocker levers for controlling the operation of the motor permitting the motor to be operative to raise the platform and lift the pile of articles thereon when the uppermost article is in a predetermined position and causing the motor to be inoperative after the platform has been raised sufficiently far to bring the uppermost article into another predetermined position.

8. In a dispenser for paper napkins, towels and like articles, a vertically movable platform, a motor, means for connecting the platform to the motor whereby when operative the motor raises the platform to lift a pile of superimposed paper napkins, towels and like articles placed thereon, a pair of oppositely disposed pivotally mounted rocker levers each adapted at one edge to bear against opposite edge portions of the uppermost article in the superimposed pile thereof, a rocker bar, means actuated by one of the said rocker levers for swinging the rocker bar, and devices actuated by the rocker bar for controlling the motor permitting the motor to be operative when the uppermost article in the superimposed pile is in a position permitting the rocker lever to descend a sufficient extent to free the means for operating the rocker bar and causing the motor to be inoperative after the platform has been raised sufficiently far to cause the superimposed pile of articles thereon to raise the rocker lever sufficiently far to actuate the means for moving the said rocker bar.

9. In a dispenser for paper napkins, towels and like articles, a vertically movable platform, a motor, means for connecting the platform to the motor whereby when operative the motor raises the platform to lift a pile of superimposed paper napkins, towels and like articles placed thereon, a pair of oppositely disposed pivotally mounted rocker levers each adapted at one edge to bear against opposite edge portions of the uppermost article in the superimposed pile

thereof, a rocker bar, a lever operated by one of the rocker levers, a link connecting the said lever with the rocker bar, and means operated by the rocker bar for controlling the operation of the motor whereby when the position of the uppermost article in the superimposed pile thereof permits the said rocker lever to fall sufficiently far to cause the finger carried thereby to disengage the said lever, the motor is operative and raises the platform until the superimposed pile of articles thereon raises the said rocker lever to position in which the finger thereof actuates the said lever and through the said link operates the rocker bar to make the motor inoperative and thereby stop the platform.

10. In a dispenser for paper napkins, towels and like articles, a vertically movable platform, a motor, a brake associated with the motor, devices for connecting the platform to the motor so that when operative the motor raises the platform to lift a pile of superimposed paper napkins, towels and the like placed thereon, a pair of pivotally mounted rocker levers adapted at corresponding edges to bear against the op-

positely disposed edge portions of the outermost article in the superimposed pile thereof, a finger carried by one of the said rocker levers, a lever adapted to be engaged by the said finger, a rocker bar, a link connecting the said lever with the rocker bar, and an arm carried by the rocker bar and adapted to engage with the brake of the said motor whereby when the said rocker lever is permitted to descend to the position in which the finger carried thereby frees the said lever the rocker bar and the arm carried thereby effect the release of the motor brake permitting the motor to become operative to raise the said platform until the superimposed pile of articles thereon raises the said rocker lever to a position in which the finger carried thereby actuates the said lever causing the said link to swing the said rocker bar to move the arm carried thereby into contact with the motor brake to set the same and to thereby cause the motor to become inoperative.

Signed by me this 6th day of October, 1924.

JOHN O. HUNT.
